UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

STEAM BOILER

Application filed January 15, 1926. Serial No. 81,370.

My present invention relates to water tube steam boilers, and particularly to boilers in which the gases flow across the tubes, and will be best understood from the following description and the annexed drawings, in which Fig. 1 is a vertical section of a typical form of Stirling boiler embodying my invention; Fig. 2 is a section on the line 2—2 of Fig. 1; Fig. 3 is a section on the line 3—3 of Fig. 1; Fig. 4 is a section on the line 4—4 of Fig. 1; Fig. 5 is a section on the line 5—5 of Fig. 1; Fig. 6 is a view of a portion of the baffle and tubes looking from the rear of the middle bank 15 of tubes in Fig. 1; Fig. 7 is a section on the line 7—7 of Fig. 6; Fig. 8 is a view of a portion of the baffle and tubes looking from the plane 8—8 of Fig. 9; Fig. 9 is a section on the line 9—9 of Fig. 8; Fig. 10 20 is a view of the rear of the middle bank of tubes in Fig. 1 looking from the plane 10—10 in that figure; Fig. 11 is a view of the rear bank of tubes in Fig. 1 looking from the plane 11—11 of that figure and 25 with the rear row of tubes in that bank omitted, and Figure 12 is a view corresponding to Figure 1 but showing the invention as used in a slightly different type of furnace.

Like reference characters indicate like parts in the different views.

In the illustrative embodiment, the boiler is provided with upper steam and water drums 10, 11 and 12 and a lower water drum 13, these drums being connected by banks of tubes 14, 15 and 16 in the usual manner, the front drum 10 and the middle drum 11 being connected by water circulators 17 and the front and middle drums being connected by steam circulators 18 and the middle and rear drums by the steam circulators 19.

The steam outlet 20 is on the middle drum 11 and is connected to the inlet header 21 of a U-tube superheater having an outlet header 22, these two headers being connected by a plurality of U-tubes 23 in the usual manner.

The usual furnace chamber is provided 45 having a fuel gas inlet 24 and a grate 25,

the arch 26 being provided to direct the hot gases toward the lower portion of the front bank of water tubes. A gas outlet 27 is provided at the rear of the rear bank of tubes.

In the arrangement which I have provided the gases, instead of flowing longitudinally of the tubes as is customary in this type of boiler, are directed substantially at right-angles to the tubes in the several banks. As best shown in Fig. 3, the tubes 14, which are arranged in the usual manner in rows extending across the boiler with the tubes in each row spaced apart, are provided with a plurality of baffles each 55 made up, in the illustrative form, of a vertical row of tiles closing the space between alternate pairs of the tubes in the row with which the baffle is associated, each baffle extending from side to side of the boiler. 60 The front baffle is made up of tiles 28, the middle baffle of tiles 29 and the rear baffle of tiles 30. It will be noted that in the preferred form, the openings in the respective baffles are arranged in staggered relation so that the tiles 29 are in the rear of 65 openings formed in the baffle at the front of the bank and also in front of openings formed in the baffle at the rear of the bank. 70

In the rear of the front bank of tubes 80 is a baffle 31 in front of the superheater headers, this baffle being supported in any desired manner, as, for instance, partly by the tiles 30 and partly by supports 32 connected to some of the tubes of the front row 85 of the middle bank of tubes.

At the rear of the middle bank of tubes 15 is a baffle made up, in the illustrative form, of separate metallic plates 33, each held to the tubes of the rear row of the 90 bank by U-shaped members 34. The plates 33 are arranged so that their edges across the boiler are spaced apart a sufficient distance to permit each plate to expand without interference with its neighbor and each member 34 is connected to an edge of a 95 pair of adjacent plates.

The plates 33 are provided with slots or 100 openings 35 each preferably relatively narrow and relatively short with their long

dimensions substantially parallel to the tubes and each preferably positioned closely adjacent one of the tubes 15. The openings 35 are thus arranged in rows extending 5 across the boiler and the openings in successive vertical rows are staggered, as best shown in Fig. 6, so that for any given tube 15, an opening is adjacent one side of that tube and the next lower opening is adjacent 10 the opposite side of the tube and so on throughout the length of the baffle. Between the two rearmost rows of tubes 16 is a baffle similar to that just described and made up of plates 36 having openings 15 37 and attached by members 38 in a manner similar to that just described for the baffle made up of the plates 33, the openings 37 being arranged in a manner similar to that of the openings 35. 20 It will be noted that the baffles in the front bank do not extend entirely to the drum 10, but, if desired, they may be continued to that drum. Similarly, it will be noted that the baffle 33 is closed at the top 25 and bottom between the drums 11 and 13 and similarly this baffle may be made of less length, if desired. The baffle 36 may be continued to the lower drum 13, if desired. 30 With the arrangement described, the gases from the furnace chamber, whether supplied from gaseous or finely divided fuel as through the inlet 24 or from solid fuel on the grate 25, flow first through the 35 openings in the baffles in the front bank of tubes, this flow being substantially at right-angles to the tubes and, by reason of the staggering of the openings in the baffles in this bank, the gases are diverted from 40 their normal path as they flow across the bank. The flow across the bank 14 is rendered approximately uniform, by reason of the free passage for gases provided adjacent the top of the bank, and the baffled 45 path provided for the gases across the lower part of the bank. By having the front baffle made up of the tiles 28 closely adjacent the front of the bank, proper temperatures in the combustion chamber may be maintained 50 which would not otherwise be possible.

Preferably, I make the baffles in the front bank of tile because of the greater heat of the gases passing across the front bank but the baffles in or on the middle and rear 55 banks are conveniently made of metal plates and such metallic baffles can be maintained both because of the lower temperature of the gases flowing over such banks as well as the contact between the tubes with which 60 such respective baffles are associated.

By arranging the openings 35 and 37 in the respective baffles in the middle and rear banks in the manner indicated, the gases are directed closely in contact with the several 65 tubes and, by reason of their staggered

relation, the flow of the gases in definite channels is prevented and improved heat transmission obtained thereby. Moreover, the positioning of the openings closely adjacent the tubes to which the baffle plates are attached causes the gases to impinge on the tubes of the next row. This creates a turbulence and prevents the flow of the gases in lanes. 70

The baffle 31 prevents the direct impingement of the gases flowing through the baffle 30 on the superheater headers and, at the same time, the superheater tubes themselves are contacted with the gases after they have passed the first bank of water tubes. 75

In Figure 12 the invention is shown as applied to a furnace which does not employ the arch 26. While the invention may be used with either type of furnace it is preferable to use it with a furnace of the type shown in this figure. Similar parts have been designated by similar numerals and, therefore this figure will not be described in detail. With the exception of the arch 26 the structure shown in this figure is substantially identical with what is shown in Figure 1. 80

While I have illustrated my invention in connection with a boiler having upper and lower drums, it will be understood that certain features of my invention may be used with other tube arrangements. 95

I claim:

1. In a water tube steam boiler, upper and lower water chambers, a bank of tubes arranged in rows and connecting the water chambers, the tubes being spaced apart in the rows, a furnace chamber in front of the bank, a gas outlet at the rear of the bank, and a baffle extending across the boiler behind one of the rows of tubes, said baffle having openings therein adapted to cause the furnace gases to flow therethrough substantially at right-angles to the tubes and said baffle comprising a plurality of separate plates and connections between each plate and the tubes of the adjacent row.

2. In a water tube steam boiler, upper and lower water chambers, a bank of tubes arranged in rows and connecting the water chambers, the tubes being spaced apart in the rows, a furnace chamber in front of the bank, a gas outlet at the rear of the bank, and a baffle extending across the boiler behind one of the rows of tubes, said baffle having openings therein adapted to cause the furnace gases to flow therethrough substantially at right-angles to the tubes, and said baffle comprising a plurality of separate plates and connections between each plate and the tubes of the adjacent row, the adjacent vertical edges of the plates being positioned behind a tube.

3. In a water tube steam boiler, upper and lower water chambers, a bank of tubes

- arranged in rows and connecting the water chambers, the tubes being spaced apart in the rows, a furnace chamber in front of the bank, a gas outlet at the rear of the bank, and a baffle extending across the boiler behind one of the rows of tubes, said baffle having openings therein adapted to cause the furnace gases to flow therethrough substantially at right-angles to the tubes, said 10 openings being relatively short and narrower than the spaces between the tubes, said openings being arranged in rows vertically with the openings in successive rows staggered and each positioned closely adjacent a tube. 15
4. In a water tube steam boiler, upper and lower water chambers, a plurality of banks of water tubes connecting said water chambers, said tubes being arranged in rows 20 across the boiler with the tubes spaced apart in the rows, a furnace chamber in front of the front bank of tubes, a gas outlet at the rear of the rear bank of tubes, a baffle in the front bank extending across the bank 25 and vertically for at least the major portion of the length of the tubes and having openings adapted to cause the gases to flow across the bank substantially at right-angles to the tubes, and a superheater behind the 30 front bank, said superheater having inlet and outlet headers extending across the boiler in the rear of said baffle in the front bank, and a solid baffle between the front bank and said headers, to prevent impingement on said headers, of the streams of gases 35 flowing through said openings. 40
5. A water tube steam boiler having water tubes arranged in rows and a metallic baffle extending across the boiler adjacent to one of said rows, said baffle comprising a plurality of separate metallic plates and connections between each plate and the tubes of the adjacent row, the adjacent edges of the plates being positioned behind a tube in said 45 row, each of the plates having a plurality of rows of openings therein, each narrower than the space between the tubes in the row and each opening positioned closely adjacent a tube. 50
6. A water tube steam boiler having water tubes arranged in rows and a metallic baffle extending across the boiler adjacent to one of said rows, said baffle comprising a plurality of separate metallic plates and connections between each plate and the tubes of the adjacent row, the adjacent edges of the plates being positioned behind a tube in said 55 row, each of the plates having a plurality of rows of openings therein, each narrower than the space between the tubes in the row and each opening positioned closely adjacent a tube. 60
7. A water tube steam boiler having tubes 65 arranged in rows, and a baffle extending across the boiler adjacent to one of said rows, said baffle comprising a plurality of separate plates and connections between each plate and the tubes of the adjacent row, the adjacent edges of the plates being positioned behind a tube in said row, and each plate having an opening therein narrower than the space between the tubes in the row, and positioned closely adjacent a tube. 70
8. A water tube steam boiler having water tubes arranged in rows and a baffle extending across the boiler adjacent to one of said rows, said baffle comprising a plurality of separate plates and connections between each plate and the tubes of the adjacent row, the adjacent edges of the plates being positioned behind a tube in said row, each of the plates having a plurality of openings therein, each narrower than the space between the tubes in the row and each opening positioned closely adjacent a tube, and the openings being staggered relatively to each other. 75
9. In a water tube steam boiler, an upper and a lower water chamber connected by a vertically extending bank of tubes, a furnace chamber in front of said bank and having a source of heat adjacent its bottom, said tubes being arranged in rows across the boiler, and a plurality of baffles each extending across the boiler and having openings to permit certain of the gases from the furnace chamber to flow transversely through the bank, said baffles terminating below said upper chamber to permit gases to flow unbaffled 80 over the ends of the tubes. 85
10. In a water tube steam boiler, an upper and a lower water chamber connected by a vertically extending bank of tubes, a furnace chamber in front of said bank and having a source of heat adjacent its bottom, the gases from said source flowing transversely of said bank, means baffling said flow across the lower portion of the bank, and means forming a passage across the upper portion of 90 the bank. 95
11. A water tube steam boiler having tubes arranged in rows, and a baffle extending across the boiler adjacent to one of said rows, said baffle comprising a plurality of separate plates and connections between each plate and the tubes of the adjacent row, said plates having a plurality of openings, each opening being narrower than the space between the tubes and positioned closely adjacent to a tube. 105
